UNITED STATES PATENT OFFICE.

ARTHUR W. LE BOEUF, OF WOONSOCKET, RHODE ISLAND, ASSIGNOR TO ELECTRIC COMPOSITOR COMPANY, OF NEW YORK, N. Y., A CORPORATION OF NEW JERSEY.

SLUG-EXPELLER MECHANISM FOR LINE-CASTING MACHINES.

1,080,570.

Specification of Letters Patent.

Patented Dec. 9, 1913.

Application filed January 15, 1913. Serial No. 742,088.

To all whom it may concern:

Be it known that I, ARTHUR W. LE BOEUF, a citizen of the United States, residing at Woonsocket, in the county of Providence and State of Rhode Island, have invented a certain new and useful Improvement in Slug-Expeller Mechanism for Line-Casting Machines, of which the following is a full, clear, and exact description.

This invention is for use as part of a machine in which line-long printing slugs or type bars are cast from assembled lines of matrices, are trimmed to uniform size, and are delivered into a galley. In such machines are many movable parts which are concerned in the casting and delivery of the type slugs; and in order that the desired results shall be attained without breakage or other disaster, it is necessary that said parts move in proper synchronism through their entire cycles of operation. Each of such machines has a movable mold, which moves between the casting and ejecting positions, and vice versa. Also there are side trimming knives before which the mold should come to rest when it is in the slug ejecting position. Also there is an expeller blade which, by its movement, forces the type slug out of the mold and between the trimming knives and to the mechanism by which the slug is delivered to the galley.

The present invention relates to the mechanism for moving said expeller blade; and the object is to provide suitable mechanism for this purpose which will operate when and only when the movable mold has taken its proper position behind the trimming knives and in front of said expeller blade.

The invention includes a guided ejector slide to which the ejector blade is secured, a power driven movable member, a hook arm movably mounted on the slide and adapted for engagement with said movable member, and means normally holding said hook out of the engaging position, and means whereby the mold in the last part of its movement to the ejecting position will cause the release of this hook, so that it may, when the mold has reached the ejecting position, move into such operative engagement with the movable member, that the latter may move the ejector slide on its slug ejecting journey.

The precise novel combinations of parts which constitute the present invention are

shown in the accompanying drawing, and hereinafter described and pointed out definitely in the appended claims.

In the drawing, Figure 1 is a plan view of slug ejecting mechanism and associated parts embodying this invention, when the mold is in the ejecting position. Fig. 2 is a plan view of certain parts, which are shown in Fig. 1, when the said parts are in the position they occupy just before the mold reaches the ejecting position. Fig. 3 is an elevation of the mechanism shown in Fig. 1 as viewed from that side thereof which is at the top of Fig. 1. Fig. 4 is a detached rear view of the plunger R and associated parts. Fig. 5 is an elevation of the same mechanism which is shown in Fig. 1, as viewed from the left side of Fig. 1.

The invention in the precise form shown is contrived with special reference for use in a machine, wherein the mold M moves in a straight horizontal path backward and forward between the ejecting and the casting positions. The invention is also particularly contrived with reference to its use in a machine wherein the power to move, through their several cycles, all of the parts concerned in the casting and slug ejecting mechanism is taken from a single shaft A, which, at the will of the operator is caused to turn through one complete revolution, and to then stop. In that machine, when the shaft stops, the movable mold comes to rest, or should come to rest in the slug ejecting position. The mold which is shown sufficiently for the present purpose may be substantially such as is shown and described in Letters Patent No. 1,027,551. That is to say, the mold proper of part M in which the mold slot is formed, is carried by a saddle M¹ to which the power to move the mold is applied, while the mold proper is movably supported upon that saddle and is normally held in the desired relation thereto. In case the mold proper meets with any obstruction to its movement into the ejecting position, the saddle may move without breaking anything. Commonly, of course, there is no interference with the complete movement of the slot-carrying part of the mold into the ejecting position; but something may get in the way of the mold, for example, the chips which result from the trimming of the slug to size may fly into some position such as to interfere with the

complete movement of the mold to the ejecting position. Obviously, the slug ejecting slide will cause something to break if it starts on its slug ejecting movement when 5 the mold is in a position such that, instead of engaging only the slug in the mold slot, the ejector blade engages some part of the mold.

The mechanism through which the power 10 shaft A imparts its required backward and forward movement to the mold is not a part of this invention, and therefore is not shown; but such mechanism may be substantially like that which is shown and described 15 in my prior application, Serial Number 736,489, filed December 13, 1912. On this shaft A is a cam *a*, which, by its action on an arm *b*, causes the rocking of rock shaft B.

20 G represents the guided expeller slide which is movable horizontally in a path at right angles to the path of the mold; that is to say, the mold moves forward and backward, and the ejector slide moves from right to left, and vice versa. The expeller blade *g* is fixed to this slide. The mold path is between the expeller blade and trimming knives K. The expeller slide, and the trimming knives are placed in such position that 25 when the mold comes to rest in the expelling position the expeller blade in its forward movement will enter the mold slot and push the slug therefrom and between the trimming knives.

30 H represents a pivoted lever in bell crank form. The substantially horizontal arm of this lever is connected by links J, J¹ and I with an arm *b*² fixed to the rock shaft B, before mentioned.

35 A hook N is pivoted on a horizontal pivot to the expeller slide and extends rearwardly therefrom. It has a hooked shape notch *n* in the under side of its rear end, which is adapted to fall over and embrace a pin *h* carried by the upper end of the bell crank H. One wall of this notch extends downward considerably farther than the other, so that, when the hook is in its normally 40 raised position, as shown in Fig. 5, and the bell crank lever is rocked in one direction the pin *h* will engage the hook and thereby move it and the slide G in the slide retracting direction; but if the bell crank lever H is rocked in the contrary direction, pin *h* 45 will move under and out of contact with the said hook. This hook N has an upwardly projecting tail piece *n*¹ which normally,—that is to say, when the expeller slide is at rest in its retracted position, rests against 50 the expeller preventer P, and thereby the hook is held in its elevated position. This expeller preventer is a block fixed to a plunger R which is movable in a horizontal direction at right angles to the direction of the 55 expeller slide. This plunger is subject to

the influence of a spring *r* tending to move it toward the left side of Fig. 1. This block has in it a notch or gap *p* into which, when the plunger R has been moved toward the right, as shown in Fig. 1, a sufficient distance, the tail piece *n*¹ of the hook lever N may drop into said gap, and thereby permit the hook shaped rear end of lever N to drop down over pin *h*. This plunger R carries on its outer end and pivoted to it on a vertical pivot a trigger T which, by virtue of a small plunger *t* and a spring *t*¹ tends to assume the position shown in Fig. 2. When in this position the short arm of this trigger lies just inside of and in engagement with 70 the side of a lever U,—the other end of which lever lies in the path in which the slot-carrying part M of the mold moves in going to the slug ejecting position. When the mold moves into the proper slug ejecting position, this slot-carrying part M of the mold engages the lever U, or rather it engages an adjustable set screw *u*¹ in the end of said lever, and thereby rocks the lever. The other end of the lever, by its engagement with the short arm of the trigger, will move said trigger and the plunger R, to which it is pivoted, in opposition to the plunger spring until the gap *p* in said plunger is brought into alignment with the tail 75 piece *n*¹ of the hook N. Thereupon this hook drops down into engagement with the pin *h* on the bell crank lever H. When this has been accomplished, the rock shaft B will be rocked in the direction such that, 80 through the described intermediate mechanism, the horizontal arm of the bell crank lever will be pulled down, and the vertical arm thereof moved toward the right, as shown in Fig. 5. The pin *h* carried by said 85 lever being in operative engagement with the hook N, will push it; and the hook will, in turn, push the expeller slide which carries it in the slug ejecting direction, with the result of pushing the slug out of the 90 properly positioned mold slot and between the trimming knives.

95 The expeller slide carries an adjustable set screw Y placed so that just as the slide has finished its slug ejecting movement, this set screw will engage with the long arm of the trigger T and will rock it on its pivot into the position shown in Fig. 1. This frees the trigger and plunger R from restraint; whereupon the plunger will be moved by its 100 spring back to its normal position. In so moving it carries the trigger with it, and thereby the short end of the trigger is left 105 engaging with the end instead of the side of lever U, which holds the trigger in this position as shown in Fig. 1, so long as lever U remains in the described position. But 110 when the mold is moved away from the ejecting position lever U is freed from restraint. Thereupon it will be moved by 115

its spring u to the position shown in Fig. 2; following which the trigger will be moved by its spring to the position also shown in the same figure. When the expeller slide 5 has been moved to its retracted position, the tail piece n^1 on hook lever N will engage with the expeller preventer P ; and its hook shaped end will thereby be lifted to the position shown in Fig. 5.

10 The lever U , as shown, is made of two pieces U , U^1 , both hung on the same pivot. This last named part is connected with the adjacent part U^1 of the member U by means of a spring pin Z . By withdrawing this 15 pin, the two parts of the lever may be disconnected, and this will permit the part U^1 to be swung out of the way of the mold so that the mold may be removed if occasion for so doing occurs, because the lever U does 20 not project into the path of said mold.

From the foregoing it is quite evident that if the mold does not move completely into the ejecting position, it will not sufficiently rock lever U , and therefore the 25 mechanism operated thereby will not be moved so as to allow the hook shaped lever N to drop. In that event, although the bell crank lever H will be rocked as usual, this 30 rocking movement will cause no movement of the ejector slide in the slug ejecting direction.

Having described my invention, I claim:

1. In expeller mechanism for line casting machines, the combination of a movable 35 mold, and an expeller slide carrying an expeller blade, with a movable slide-operating member, a hook movably secured to said slide and adapted to engage with said member, means which normally hold said hook 40 out of such engagement, and a train of mechanism to release said hook, one member of said train of mechanism being extended into the path over which the mold must travel as it moves to the ejecting position.

45 2. In expeller mechanism for line casting machines, the combination of a movable mold, and an expeller slide carrying an expeller blade, with a movable slide-operating member, a hook movably secured to said 50 slide and adapted to engage with said member and provided with a tail piece, a train of mechanism of which one terminal member lies in the path of and is adapted to be engaged by said tail piece when the slide 55 is moving to its retracted position and the other terminal member being extended into the path of the movable mold and adapted to be engaged thereby as the mold moves to the ejecting position.

60 3. In expeller mechanism for line casting machines, the combination of a movable mold, and an expeller slide carrying an expeller blade, with a rocking lever carrying pin, a hook movably secured to said slide, 65 and adapted to engage with said pin, means

which normally hold said hook out of such engagement, and a train of mechanism to release said hook, one member of said train of mechanism being extended into the path over which the mold must travel as it 70 moves to the ejecting position.

4. In expeller mechanism for line casting machines, the combination of a movable mold, and an expeller slide carrying an expeller blade, with a movable slide-operating member, a hook movably secured to said slide and adapted to engage with said member and provided with a tail piece, a spring actuated plunger carrying an expeller preventer adapted to engage the said tail piece 75 and so hold the hook out of engagement with said member, a pivoted lever having one end projected into the path over which the mold must travel in moving to the ejecting position, and mechanism intermediate of said lever and said plunger through which when the lever is moved by the mold the plunger will be moved to carry the expeller preventer 80 out of engagement with said tail piece.

5. In expeller mechanism for line casting 85 machines, the combination of a movable mold, and an expeller slide carrying an expeller blade, with a movable slide-operating member, a hook movably secured to said slide and adapted to engage with said member, and provided with a tail piece, a spring actuated plunger, an expeller preventer carried thereby for engaging the said tail piece to hold the hook out of engagement with said operating member, a lever of which one 90 end is projected into the path over which the mold must travel in moving to the ejecting position, and a trigger pivoted to said plunger and adapted to be engaged by said lever.

6. In expeller mechanism for line casting machines, the combination of a mold, and an expeller slide carrying an expeller blade, with a movable slide-operating member, a hook movably secured to said slide and adapted to engage with said member, and provided with a tail piece, a spring actuated plunger, an expeller preventer carried thereby for engaging the said tail piece to hold the hook out of engagement with said operating member, a lever of which one end is projected into the path over which the mold must travel in moving to the ejecting position, a trigger pivoted to said plunger and having one short arm arranged to engage 100 either with the side or end of said lever according to the position it occupies, a spring acting to move said trigger into the position where its short arm will be engaged by the side of said lever, and a projection on the 105 slide adapted to engage the other arm of the trigger and move it into the position such that it will engage the end of said lever.

7. In expeller mechanism for line casting machines, the combination of a movable 110

mold, and an expeller slide carrying an expeller blade, with a movable slide-operating member, a hook movably secured to said slide and adapted to engage with said member and provided with a tail piece; a train of mechanism of which one terminal member lies in the path of and is adapted to be engaged by said tail piece when the slide is moving to its retracted position and the other terminal member being extended into the path of the movable mold and adapted to be engaged thereby as the mold moves to the ejecting position, the last mentioned member being a lever formed of two pieces 15 hung on the same pivot, and means for connecting and disconnecting said two pieces.

8. In expeller mechanism for line casting machines, the combination of a movable mold, and an expeller slide carrying an expeller blade, with a movable slide operat-

ing member, a hook movably secured to said slide and adapted to engage with said member, means which normally hold said hook out of such engagement, and a lever made of two pieces both hung on the same pivot, the end of one piece being projected into the path over which the mold must travel in moving to the ejecting position, means for connecting and disconnecting the two pieces of the lever, and means operated by said lever for controlling the position of the means which normally hold the hook out of operative engagement with the operating member.

In testimony whereof, I hereunto affix my signature in the presence of two witnesses.

ARTHUR W. LE BOEUF.
